UNITED STATES PATENT OFFICE.

EUGENE H. TAYLOR, OF HYDE PARK, MASSACHUSETTS.

PAPER-BOX MACHINE.

1,079,275.

Specification of Letters Patent.

Patented Nov. 18, 1913.

Application filed September 15, 1909. Serial No. 517,859.

To all whom it may concern:

Be it known that I, EUGENE H. TAYLOR, a citizen of the United States, residing at Hyde Park, county of Norfolk, State of

5 Massachusetts, have invented a certain new and useful Improvement in Paper-Box Machines, of which the following is a specification, reference being had therein to the accompanying drawings.

10 This improvement relates to paper-box machines and more especially to machines which are used for cutting or scoring the paper stock.

The nature and objects of the invention 15 are fully set forth in the following description taken in connection with the accompanying drawings, and the novel features thereof are pointed out and clearly defined in the claims at the close of this specification.

20 In paper-box machines, such for example as scoring and cutting machines, the sheets of paper board are passed over a work-support at the front of the machine, through the scoring or cutting rolls and pass onto

25 a table located at the rear of the scoring or cutting mechanism. The successive sheets which are scored or blanks which are cut pile up on this table at the rear of the scoring or cutting mechanism, and it is desir- 30 able that they shall pile up evenly so that they may be in shape to be removed speedily and conveniently by the operator when the table on which they are received is full, or a certain number of sheets or blanks have

35 passed through the machine. To facilitate this even piling up of the blanks or sheets, the table on which they are received should be adjustable so as to accommodate small or large blanks or blanks of any intermedi- 40 ate size, since one scoring or cutting machine is used for a large variety of blanks or sheets. By the employment of my invention I am enabled to provide a table which may be adjusted or set to receive

45 blanks or sheets of any size and from which, when a certain number of blanks or sheets have been passed through the machine, the operator may readily remove them.

In the drawings,—Figure 1 is an end ele- 50 vation of a scoring machine embodying my invention. Fig. 2 is a plan view thereof.

The frame of the machine is shown at A, the top portion thereof in which the rolls are journaled is shown at B, and the work- 55 support at C.

D, D, are brackets secured to the frame A, and serving to support the work-support C.

The scorer is shown at E, and the coöperating supporting feed-roll at F. These parts are of well known construction and will not 60 require a more detailed description.

The work-supporting table is shown at 2. It is provided at its rear edge with an end piece or tail-board 3 which is hinged, as shown at 4, to the rear edge of the table 2 65 so that, when the stock is to be removed from the table, the piece 3 may be dropped into the position shown by dotted lines 5. This permits the operator to take the stock off of the table 2 without lifting it over the 70 tail-board 3.

For the purpose of retaining the board 3 in its uppermost position, as shown by full lines Fig. 1, a spring-catch of usual construction, indicated at 6, may be employed. 75

The said catch is secured in a groove 33 in the edge of the table, and when it is desired to drop the tail-board, it is only necessary to press downwardly the outwardly projecting end of the spring-catch. The for- 80 ward edge of the table is recessed as shown by dotted line 30, Fig. 2, forming at each side of the table at the forward end projec- 85 tions 31 and 32 by means of which the forward end of the table is supported inside the frame of the machine. Inside the said

end frames of the machine, a suitable ledge or inward projection 7 is formed, one on each of the end frames, and these projections serve to support the table 2 and to 90 permit it to be slid forwardly or backwardly so that it may be set to project a greater or less distance at the rear of the machine as may be desired to accommodate larger or smaller sheets or blanks. If desired, in- 95 stead of a fixed ledge or projection, two or more friction rolls, 8, 8, may be mounted on studs on the inside of the end frames and the edges of the table will rest on these rolls.

The under side of the table is provided 100 with a shallow recessed track 9 of the curved shape shown in Fig. 2. Two swinging bracket arms 10, one at each side of the machine are provided, the said arms being pivoted at their inner ends to lugs 11 by 105

means of a vertical pin 12, which passes through the lugs and through bosses 13 and 14 formed on the inner end of the said bracket arm 10, as will be clear from Fig. 1. The outer or free end of the arm 10 is 110 provided with a boss 15 having a vertical hole therethrough to accommodate the vertically movable pin 16. A set screw 17 is provided in the boss by means of which
